CONNECTER PLUG

Robert John Feuchter, Irvington, N. J.

Application May 26, 1934, Serial No. 727,823

6 Claims. (Cl. 173—332)

This invention relates to improvements in connector plugs for providing a detachable electric connection between an electric source of supply and electric appliances.

- 5 One object of this invention is to provide an improved connector plug having a body formed of two parts with the surface of separation of the parts such as to give maximum strength to the body.
- 10 Another object of this invention is to provide an improved connector plug having a body formed of two parts joined together by means which do not loosen, as do nuts and screws.

Another object of this invention is to provide 15 an improved connector plug of maximum simplicity of design and minimum cost of construction and assembly.

Another object of this invention is to provide 20 an improved connector plug having improved contacts to avoid arcing and heating.

With the above and other objects in view, this invention includes all improvements over the prior art which are disclosed in this application.

In the accompanying drawing in which one 25 way of carrying out the invention is shown for illustrative purposes:

Fig. 1 is a front elevation, with half in central section, of a connector plug illustrating one embodiment of the invention;

30 Fig. 2 is a right side elevation of Fig. 1 with the locking clip omitted;

Fig. 3 is a view similar to Fig. 1 of the lower part of the two-part body;

Fig. 4 is a top plan view of Fig. 3;

35 Fig. 5 is a view similar to Fig. 1, of the upper part of the two-part body;

Fig. 6 is a bottom plan view of Fig. 5;

Fig. 7 is a side elevation of one of the coil-spring contacts;

40 Fig. 8 is a top plan view of Fig. 7;

Fig. 9 is a central vertical sectional view of one of the locking clips; and

Fig. 10 is a left side elevation of the locking clip shown in Fig. 9.

45 In the description and claims, the various parts are identified by specific names for convenience, but they are intended to be as generic in their application as the prior art will permit.

Referring to the drawing, 20 is the two-part body formed of the upper body part 21 and the lower body part 22, which two parts are preferably formed of insulating material, such for example, as cold molded or "Bakelite" composition.

50 The two body parts 21 and 22 have their respective adjoining surfaces 23 and 24 abutting

5 along the plane or surface 25 which extends transversely of the longitudinal axis of the two-part body 20. The upper body part 21 has a cylindrical centering recess 26 in which fits a centering lug 27, which latter is formed as part of and projects from the lower body part 22.

Connecting with the centering recess 26 is a conductor passage 28, the outer portion 29 of which flares outward or tapers inward in conical form, thus minimizing the effect of the weight 10 of the electric cord or cable on the connector plug. Upper body part 21 has two housing cavities or recesses 30, 31 on opposite sides of the centering recesses 26 with the passages 32 connecting the centering recess 26 with the housing 15 recesses.

The centering lug 27 on the lower body part 22 has the two opposite cylindrical surfaces 33 (Fig. 4) of a diameter to fit the centering recess 26. The lug 27 also has two diverging passages 20 34, which in the form illustrated in the drawing, are formed by concave surfaces of cylindrical form on the lug 27 to form a separating projection 34a to separate the electric wires.

The lower body part 22 has a pair of chambers 25 35, each chamber connecting with an exit opening 36 of reduced size, forming ledges 37. Pairs of recesses 38 and 39 are provided in the parts 21 and 22 respectively.

Each of body parts 21 and 22 has opposite, half-round side lugs 40 and 41. The lugs 40 form one pair and the lugs 41 form another pair. Each pair of lugs 40 and 41 provides a conical clip-locking surface 42 (Figs. 1 and 2) and an oppositely directed conical clip-holding surface 43. 35 Each locking clip 44 is preferably made of spring metal, such for example as spring brass, and is formed with slots 45 to provide spring gripping or holding fingers 46 which can be forced over the large diameter edge 47 (Fig. 2) of each pair 40 of side lugs to snap into engagement with the conical holding surface 43 with the cylindrical locking surface 48 in locking engagement with the conical locking surface 42 to thus hold each pair of side lugs and the body parts 21 and 22, 45 centered and firmly locked together. Although the locking clips 44 will not come off or loosen of themselves, they can be pried off and put back on whenever desired.

Each of the two spring contact members 49 is 50 preferably made of an integral coil of spring wire of suitably good electrical conductivity, and before being placed in the position shown in Fig. 1, is somewhat longer than illustrated in Figs. 1 and 7, being shortened by compressive engagement 55

between a ledge 37 of lower body part 22 and a portion of surface 23 of upper body part 21. The lower portion of the coil of each contact member 49 is flared out in the shape of a cone larger than the main portion of the coil in order to facilitate easy entrance of attachment or contact pins of appliances into the coil contacts 49.

At the upper end, each contact 49 is provided with an offset arm 50 which rests in recesses 38, 10 39, thus preventing contacts 49 from turning. Connected to the looped upper end 51 of each contact 49 by a bolt 52, is an electric wire 53 which extends through passages 32 and 34 to the electric cable 54 of which each electric wire 15 forms a part, the two wires being kept separated by the separating projection 34a.

It will be observed that due to the two body parts being divided along the surface 25, instead of the usual division along a longitudinal surface 20 in the plane of the attachment pins of appliances, which divides the usual body into two thin, weak parts, the body made according to the present invention has far greater mechanical strength to withstand the bending forces which tend to open 25 the connector body or housing due to handling in attaching and removing the plug, and due to the weight of the electric cord.

When attachment or contact pins of an electric appliance are forced into the spring contacts 49, the coils of the latter are free to temporarily enlarge or expand to accommodate such attachment pins and at the same time make positive good electric contact along the attachment pins regardless of any angularity or side motion of 30 the connector plug or the appliance to which it is attached; or varying diameters of attachment pins due to wear or other reasons, thus preventing arcing and heating. When withdrawing the connector plug from attachment pins, the tension 40 of the contact springs 49 is transmitted to the ledges 37. When forcing the contact springs 49 on the attachment pins of appliances, the resulting compression is transmitted to the bottom surface 23 of body part 21.

45 The invention may be embodied in other specific forms without departing from the essential characteristics of the invention, and the present embodiment is therefore to be considered in all respects as illustrative and not restrictive, the scope 50 of the invention being indicated by the appended claims rather than by the foregoing description, and all changes which come within the range of equivalency of the claims are therefore intended to be embraced therein.

55 I claim:

1. A connector plug including: a body formed of two parts, said two parts abutting along a surface extending transversely of said body and having two pairs of locking lugs, the lugs of each 60 pair being adjacent and at a side of the body opposite from the other pair of lugs; and locking clips each locking a pair of lugs together, each locking clip having resilient means for holding it attached to a pair of lugs and relatively rigid

means to engage and hold the pair of lugs together.

2. A connector plug including a body formed of two parts, said two parts abutting along a surface extending transversely of said body and 5 having two pairs of locking lugs, the lugs of each pair being adjacent and at a side of the body opposite from the other pair of lugs; and locking clips each locking a pair of lugs together, each locking clip having resilient means for holding it attached to a pair of lugs and a relatively rigid ring portion to engage and hold the pair of lugs together.

3. A connector plug including: a body formed of two parts abutting together and having two 15 pairs of locking lugs, the lugs of each pair being adjacent and at a location opposite and spaced from the other pair of lugs; and locking clips each locking a pair of lugs together, each locking 20 clip having resilient means for holding it attached to a pair of lugs and relatively rigid means to engage and hold the pair of lugs together.

4. A connector plug including: a body formed of two parts, said two parts adjoining along a 25 plane surface extending transversely of said body; one of said parts having an electric-conductor passage leading to a cylindrical centering recess adjacent said transversely extending surface, and two connection-housing recesses, 30 one on each side of said passage; the other of said parts having a centering lug with cylindrical surface portions fitting the cylindrical surface in said centering recess, and said centering lug having diverging passages leading from said 35 electric-conductor passage to said connection-housing recesses; and locking means locking said two parts together.

5. A connector plug including: a body formed of two parts adjoining along a surface extending 40 transversely of said body; one of said parts having two contact chambers each having a reduced exit opening forming a ledge; a continuous integral wire coil contact under endwise compression in each contact chamber and having one 45 end supported by one of said ledges in one of said parts, and the other end supported by the other of said parts; and locking means locking said two parts together.

6. A connector plug including: a body formed 50 of two parts, said two parts adjoining along a plane surface extending transversely of said body; one of said parts having an electric-conductor passage leading to a cylindrical centering recess adjacent said transversely extending surface; the other of said parts having a centering lug with cylindrical surface portions fitting the cylindrical surface in said centering recess, and said centering lug having diverging passages leading from said electric-conductor passage; 60 and locking means locking said two parts together.

ROBERT JOHN FEUCHTER.
